UNITED STATES PATENT OFFICE.

OLOF A. TOFFTEEN, OF CHICAGO, ILLINOIS.

FIRE ARCH.

Application filed September 30, 1925. Serial No. 59,552.

This invention relates to improved fire arch constructions adapted to be designed for use in any desired type of boiler, the fire boxes of which are adapted to be readily equipped with the improved arch and baffle means which are preferably constructed of a carborundum product to withstand the great heat to which the arches and baffles are adapted to be subjected.

10 It is an object of this invention to provide a boiler fire box with an improved apertured fire arch having smoke and flame outlet sleeves mounted therein.

It is also an object of this invention to 15 provide a boiler fire box with an improved fire arch and baffle mechanism, said fire arch and baffle mechanism being constructed of a refractory material and having suitable air feed perforations therein, as well as escape 20 pipes or flues, permitting smoke and the flames of combustion to pass through the fire arch and through the baffle mechanisms.

It is a further object of this invention to provide a boiler fire arch constructed of 25 bricks or tiles of hollow perforated construction having perforated smoke and flame escape sleeves therein.

It is furthermore an object of this invention to provide a fire arch constructed of 30 perforated hollow tiles made of a refractory material, said tiles having flame passageways therein which also communicate with the interior of the tiles.

Another object of the invention is to 35 provide a boiler fire box fire arch constructed of a carborundum product and having air supply apertures and flame escape passageways therein to materially assist in a complete combustion of the fuel on the grate of the 40 fire box.

Still another object of the invention is to provide a boiler fire arch constructed of a plurality of bricks or tiles so formed that when the same are assembled in the form 45 of a fire arch or baffle wall, the supply of air may be augmented through suitable air supply apertures and the escape of the flames and smoke is facilitated by the provision of suitable passageways or flues for 50 the purpose.

It is an important object of this invention to provide a boiler fire arch constructed of hollow perforated carborundum material, such as fused silicon carbide, so that the fire 55 arch will not only increase the efficiency of the fuel consumption, but will also with-

stand deterioration due to the excessive heat to which the fire arch is subjected.

Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary longitudinal section through a horizontal boiler fire box equipped with an improved fire arch and baffle wall embodying the principles of this invention.

Figure 2 is a transverse section of the boiler fire box taken on line II—II of Figure 1.

Figure 3 is an enlarged detail section taken on line III—III of Figure 1.

Figure 4 is a fragmentary longitudinal section through another type of horizontal boiler, which is equipped with a modified form of fire arch.

Figure 5 is a sectional view taken on line V—V of Figure 4.

Figure 6 is a plan view of a plurality of improved fire bricks or tiles of a modified form, adapted to be assembled to form a fire arch or baffle wall.

Figure 7 is a plan view of a plurality of associated fire bricks or tiles of still another modified form.

As shown on the drawings:

The reference numeral 1 indicates a fragmentary portion of a horizontal boiler having a plurality of tubes 2 which communicate with a fire box 3. Mounted in the fire box is a fire grate 4 upon which the improved fire arch of this invention is adapted to be mounted or built.

The improved fire arch comprises a hollow rear wall constructed of a plurality of assembled hollow fire bricks or tiles 5, the lower ends of which rest on the grate and are open to permit air to pass upwardly through the grate and through said rear wall tiles. Connected with the upper ends of the rear wall tiles 5 are a plurality of arch wall tiles 6 which are built up to form an arched wall which projects forwardly from the rear wall toward the front wall of the fire box. The ends of the arched portion just described are supported by means of a plurality of hollow fire bricks or tiles 7, the lower portions of which have large openings 8 formed therein.

to afford a means whereby the heat from the fire bed may come into direct contact with the inner face of the side walls of the fire box 3. The fire bricks or tiles 7 are of a hollow construction to permit air passing upwardly through the grate to pass upwardly through said fire bricks or tiles and be discharged through a plurality of air feed perforations or apertures 9. The fire bricks or tiles 6 are also of a hollow construction and are provided with end apertures 10, upper apertures 11, bottom apertures 12 and side apertures 13. All the apertures in the fire bricks or tiles forming the upper arched wall are arranged near the upper end of the arch as clearly illustrated in Figure 1. The completed fire arch formed by means of the hollow rear wall tiles 5, the hollow upper arched wall tiles 6 and the hollow side wall tiles 7 is adapted to be mounted on the fire grate so that a large supply of air is adapted to be admitted upwardly through the passageways of the tiles 5 and 7 and through the hollow tiles 6 to permit the air to be fed or discharged into the fire box above the bed of fuel to assist in the complete combustion of the fuel. The various tiles used in the construction of the fire arch are all made of a refractory material, such as a carborundum product or of a mechanically, chemically or electro-chemically fused silicon carbide. As clearly shown in Figures 1 and 2, the upper wall fire bricks or tiles 6 are provided with large openings which extend transversely through the tiles and have securely engaged therein smoke and flame outlet sleeves, pipes or flues 14 open at both ends and provided with a plurality of air outlet passages 15 in the side walls thereof. It will thus be seen that the upper arched wall of the fire arch is of a hollow perforated construction having suitable air supply apertures therein, as well as apertured flame and smoke discharge flues or sleeves 14.

45 Suspended from the top wall of the fire box 3 by means of suitable supports 16 is an improved baffle fire wall constructed of fire bricks or tiles 17 made of a carborundum product or of a fused silicon carbide. Each of the tiles is provided with air supply apertures 18 in the top, bottom, side and end walls. Each of the baffle fire bricks or tiles is also provided with a plurality of flame and smoke escape sleeves or flues 19 open at both ends and provided with a plurality of air apertures 20 in the side walls thereof. The baffle tiles 17 are arranged, as shown in Figures 1 and 2, across the upper portion of the fire box to form a complete baffle wall, the front end of which is formed to afford an air supply channel 21, the end of which opens through the front of the fire box and is controlled by means of a damper or shutter 22. The baffle wall is also positioned above the improved fire arch to coact therewith in

securing a complete combustion of the fuel on the fire grate 4.

The apertured tiles and the sleeves thereof forming the completed fire arch and the baffle wall are constructed of fused silicon carbide or are made of a carborundum product commercially known as Carbofrax, to afford a fire arch and baffle wall construction which will stand up under the severe heat to which they are subjected. With a bed of fuel on the fire grate 4, air is admitted from the ash pit upwardly through the grate through the hollow rear tiles 5 of the fire arch and through the hollow legs or columns of the side wall tiles 7 and then circulates upwardly through the top wall tiles 6 with the air escaping through the various air outlet apertures 9, 10, 11, 12 and 13. It will thus be seen that the fire within the fire box is supplied with an additional supply of air above the fuel bed, thereby augmenting the supply of oxygen to the flames to cause a substantially complete combustion of the fuel to permit the flames and smoke to pass through the top wall of the fire arch, as well as around through the front of the fire arch. The apertured sleeves or flues 14 are provided in the tiles 6 so that a portion of the flames and smoke may pass through the top wall of the fire arch. When the shutter 22 is open, air is admitted into the front end of the baffle wall positioned across the top of the fire box above the fire arch. The air admitted into the baffle wall is permitted to escape through the various openings or apertures 18 to still further augment the supply of oxygen to the upwardly flying flames. The baffle wall is also equipped with flame and smoke sleeves or flues 19 to permit the flames and smoke to pass upwardly through the baffle wall against the top wall of the fire box which serves to direct the same out between the boiler tubes 2. The provision of the flame escape sleeves or flues in the fire bricks of the fire arch and baffle wall also permits the flames when passing through said sleeves to be augmented or supplied with additional oxygen through the apertures in said sleeves which communicate with the interior of the hollow fire bricks or tiles.

50 Figures 4 and 5 illustrate a modified form of fire arch adapted for use in the fire box of a different type of horizontal boiler 23. In this case the fire box 24 is equipped with a fire grate 25. Mounted upon the fire grate 25 is an improved fire arch consisting of a hollow rear wall made up of a plurality of hollow fire bricks or tiles 26 which are positioned to interfit with one another across the lower portion of the rear wall of the fire box. Built into the upper ends of the rear wall fire bricks 26 are a plurality of top wall fire bricks 27 which are also of a hollow construction and have air supply apertures 28 in the top, bottom, end and

55 60 65 70 75 80 85 90 95 100 105 110 115 120 125 130

side walls thereof. The top fire bricks 27 are fitted together and completely cross the fire box in an inclined plane extending upwardly toward the front end of the fire box. 5 The top wall of the fire arch is supported in position within the fire box by means of suitable piping 29 connected with the water supply system so that water may be continually circulated through the pipes of 10 the supporting frame to prevent burning up of the same. Each of the top wall fire bricks or tiles 27 is provided with flame escape sleeves or flues 30 each having a plurality of air supply apertures 31 in the side walls 15 thereof. The flames from the bed of fuel on the grate 25 are thus permitted to pass upwardly not only around the upper front end of the fire arch but are also permitted to pass through the flame escape sleeves 20 or flues 30 provided in the fire bricks 27. The flames are supplied with an additional supply of oxygen carried by the air escaping from the apertures 28 of the top wall of the fire arch. Air is also supplied through 25 the apertures 31 of the sleeves 30 to portions of the flames passing upwardly through the fire arch. It will thus be seen that the flames in the fire box are adapted to be supplied with additional oxygen to cause a substantially complete combustion of the fuel 30 and affording a particularly high temperature for the purpose of heating the boiler tubes.

Figure 6 illustrates a fragmentary portion of a fire arch wall constructed of a modified form of fire brick or tile 32 of a substantially **I** construction having side recesses 33 and a plurality of air escaping apertures 34 in all of the walls thereof. The fire bricks 32 are adapted to be positioned adjacent one another as illustrated in Figure 6 so that when in abutting relation, flame escape channels or passages 35 are afforded by the registering recesses 33 of adjacent fire bricks. The flame escape passageways 35 are the equivalent of the flame escape passages afforded by the sleeves 14 and 19 illustrated in Figure 1. Figure 7 illustrates a plurality of modified tile bricks 36 of octagonal shape, the top and bottom walls and side walls of which are provided with air supply apertures 37. When four of the fire bricks 36 are associated, as illustrated in Figure 7, flame escape passageways 38 are afforded between the respective fire bricks. It will of course be understood that the fire bricks used in the construction of the fire arches described may be of any desired design to meet requirements and furthermore may be assembled to produce an arch of proper design to fit substantially any type of boiler. The fire bricks or tiles are all made of a refractory material, such as a carborundum product or fused silicon carbide, so that the bricks or tiles will with-

stand the great heat to which they are subjected.

While two different types of horizontal boilers are illustrated in the drawings and are equipped with improved fire arches and a baffle wall, it is to be understood that fire arches and baffle walls constructed similar to those illustrated and described may be designed to meet the requirements of all types of boiler constructions. The improved fire arches and baffle walls of this invention are constructed of the improved material referred to and are of hollow construction having the required number of air supply apertures properly located therein, in addition to being equipped with the apertured flame escape sleeves except in such cases where the fire bricks are shaped to afford flame escape passageways when said fire bricks are assembled as illustrated in Figures 6 and 7 of the drawings.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with a boiler fire box, of a hollow fire arch mounted therein having air supply apertures and flame escape passageways therein, a fire baffle wall mounted in said fire box above the fire arch, with said baffle wall having air supply apertures and flame escape passageways therein, and means at one end of said fire baffle wall for controlling the passage of air therein.

2. The combination with a boiler fire box, of a hollow apertured fire arch mounted therein with the open end of said fire arch directed forwardly, apertured sleeves mounted in said fire arch, a hollow apertured baffle wall mounted in said fire box above the fire arch and projecting rearwardly from the front wall of the fire box over the fire arch, adjustable means on the front of the fire box for controlling the passage of air into the baffle wall, and apertured sleeves mounted in said baffle wall.

3. The combination with a boiler fire box, of a hollow apertured fire arch mounted therein, apertured sleeves mounted in said fire arch, a hollow apertured baffle wall mounted in the fire box and directed rearwardly above the fire arch, and apertured sleeves mounted in said baffle wall.

4. The combination with a boiler fire box, of a plurality of hollow apertured walls mounted therein and directed in opposite directions, one above the other, and apertured sleeves mounted in said walls.

In testimony whereof I have hereunto subscribed my name.

OLOF A. TOFFTEEN.
